UNITED STATES PATENT OFFICE.

MALCOME C. CAIN, OF WELCOME, FLORIDA.

MAIL-CARRIER.

No. 927,325.

Specification of Letters Patent.

Patented July 6, 1909.

Application filed September 1, 1908. Serial No. 451,191.

To all whom it may concern:

Be it known that I, MALCOME C. CAIN, a citizen of the United States, residing at Welcome, in the county of Hillsboro and State of Florida, have invented new and useful Improvements in Mail-Carriers, of which the following is a specification.

This invention relates to mail carriers, and has for an object to provide a device of this character which may be effectively used for delivering mail to post-office stations along star or rural routes.

A further object of this invention is to provide a mail carrier which may be propelled by electricity or other motive power and which will be adapted to contain mail to be delivered to postmasters, and to construct the device whereby it will be automatically stopped at each station.

Other objects and advantages will be apparent as the nature of the invention is better disclosed, and it will of course be understood that changes within the scope of the claims may be resorted to without departing from the spirit of the invention.

In the drawings, forming a portion of this specification and in which like numerals of reference indicate similar parts in the several views,—Figure 1 is a side view of the mail carrier suspended upon an elevated track, Fig. 2 is a vertical transverse sectional view on the line 2—2 of Fig. 1, Fig. 3 is a detail perspective view of one of the brake levers, Fig. 4 is a diagrammatic view. Fig. 5 is a detail perspective view of the trolley arm stop, Fig. 6 is a longitudinal sectional view showing a slightly modified form of my invention.

Referring to Figs. 1 to 5 of the drawings, there is shown a mail carrier 5 which is preferably in form of an elongated receptacle provided at one side with a hingedly mounted door 6, the same carrying a lock 7 by means of which access to the receptacle can only be gained by those possessing keys, that is to say, postmasters along rural or star routes. The receptacle has mounted upon the top thereof a bracket 8 having vertically disposed spaced pairs of arms 9, which project upwardly in a vertical plane and between each pair is rotatably mounted a guard wheel 10 for engagement beneath the head portion 11 of a T-track. The track is supported by horizontally disposed arms 12 which are connected, at their outer end, to diagonally disposed line posts 13. The just described posts

are connected by cap members 14 to similar posts 15, but which are disposed to lie at an angle opposite to the posts 13. The posts are thus disposed or formed in pairs of inverted V-form. The caps 14 are provided with a plurality of brace rods 16, and these rods, and their lower ends, are connected to the T-track as shown at 17. The arms 9 of the bracket 8 at one side of said track support or have formed integral therewith a casing 18, and projecting from said casing at the top thereof is a plurality of arms 19 which have offset portions 20 whereby said arms are disposed in spaced parallel relation to one side of said casing 18. The arms 19 and the casing 18 have mounted therebetween wheels 21 located to run or travel upon the upper edge of the portion 11 of the track. The wheels 21, and the wheels 10 previously described, are flanged, as shown, to prevent their disengagement from the track, it being understood that the lowermost wheels 10 serve as guards to prevent casual displacement of the car or the receptacle. The casing 18 has pivotally mounted thereon, as shown at 22, a trolley arm 23, which arm is provided with a laterally extending portion 24 engaged by a helical spring 25 to normally hold the trolley wheel 26 at the outer end of the arm 23 engaged with the trolley wire 27. At one side of the casing 18 is pivotally mounted as indicated at 28 a pair of arms 29, each arm being provided at its outer end with a pivotally mounted brake shoe 30 for engagement with the wheels 21, as will be hereinafter more fully described. The arms, at their inner ends, are provided with armatures 31 disposed above the cores of electromagnets 32. Each arm is provided midway between its ends with a depending finger 33 disposed between the convolutions of helical springs 34. The electromagnets 32 may receive current through a motor 35 carried by the casing 18, and which motor may be connected electrically to receive current from the trolley wire 27. In practice, a line is built along rural or star routes and mail may be deposited in the receptacle 5 by the postmaster at a central station. The mail may be suitably arranged and marked to designate the station to which it is addressed. The trolley wheel 26 is simultaneously engaged with the trolley 27 whereby said receptacle may be started upon its journey. Within a suitable distance of each station and mounted upon the posts 15 there are shown trip arms 37

adapted to engage fingers 38 carried by the trolley arms 23. It will thus be seen that after the trip arm 37, as shown in Figs. 1 and 2 of the drawings, engages the finger 38 the 5 trolley wheel 26 will be thrown out of engagement with the trolley wire, thus deenergizing the magnets 32 to free their armatures 31, and by means of the springs 34 the brake 10 shoes 30 will be engaged with the wheels 21 to effectively stop the receptacle when it arrives at its station.

In Fig. 6 of the drawings, a receptacle 39 is provided and has mounted therein upon its bottom a gasoline engine 40, the drive 15 shaft 41 of which being adapted to operate a drive chain 42 engaged with a sprocket 43 carried by an axle 44. The axle 44 is carried by brackets 45 between which are loosely 20 mounted axles 46 and 47 respectively. The respective axles are provided with wheels 48 to travel upon a track 49, and as shown, the wheel 48 is a drive wheel and its axle 46 is provided with a sprocket 50 receiving a chain 51 from a sprocket 52 upon the axle 44. The 25 receptacle in this form of my invention is preferably provided with a door 53 and said receptacle is of a size to permit the occupancy of an operator or mail sorter. A hooked arm 55 is carried by the casing 18 and 30 is engaged with said arm 23, as shown.

I claim:—

1. A device of the class described comprising a mail container, a track for suspending the same, a trolley, a trolley wheel carried by the container for engaging said trolley, a brake mechanism, and trip means for simultaneously disengaging the trolley wheel from the trolley and applying said brake mechanism.

2. A device of the class described comprising a receptacle, a track upon which said receptacle is mounted, a trolley, a trolley wheel for engaging said trolley, brake mechanism adapted to be held normally in an inoperative position, a motor, electrically connected means connecting the brake mechanism with the motor, electrical connections between the trolley wheel and the motor, and trip means for disengaging the trolley wheel from the trolley and for simultaneously throwing the brake mechanism into an operative position.

3. The combination with a track and a support therefor, of a movable receptacle mounted upon the track, a trolley, a trolley 55 wheel carried by the receptacle for engaging said trolley, an electrically controlled brake mechanism, and means for automatically applying said brake mechanism and disengaging the wheel from said trolley. 60

4. A device of the class described comprising a portable receptacle having supporting wheels, a track upon which said wheels travel, a trolley wire, a trolley wheel engaged with the wire, brake arms having brake shoes 65 for engaging the wheels, electric means for normally holding the shoes disengaged from said wheels, and automatically operated means for disengaging the trolley wheels from its wire and applying the brake shoes to 70 said wheels.

In testimony whereof I affix my signature in presence of two witnesses.

MALCOME C. CAIN.
